REMOTE RADIO CONTROL

Elbridge F. Bacon, Flint, Mich., assignor to General Motors Corporation, Detroit, Mich., a corporation of Delaware

Application December 5, 1936, Serial No. 114,326

3 Claims. (CL 116—124.1)

The present invention relates to remote control means for operating a device from a remotely positioned point and more specifically to the control of a radio receiving set from some point at a spaced distance therefrom.

With the advent of the large use of radio sets in automotive vehicles, it has become the usual custom to support the set on the dash or firewall between the engine compartment and the interior of the vehicle. Inasmuch as this is of course not accessible for tuning by the operator of the vehicle, it is necessary to provide a remote control box which can be positioned at some point near the operator so that he may tune the set without diverting his attention from the operation of the vehicle.

It is therefore the object of my invention to provide remote control means adapted to be positioned at an accessible position in a motor vehicle.

It is a further object of my invention to provide a remote control device in which all of the necessary changeable functions of operation are provided in the operation of a radio set.

It is a still further object of my invention to provide a remote control device for a radio set which is simple, sturdily constructed and of pleasing appearance.

With these and other objects in view the embodiments of my invention are disclosed in the following specification and claims and illustrated in the accompanying drawings, in which:

Figure 1 is a top plan view of my device, parts being broken away and shown in section.

Figure 2 is a sectional view taken on line 2—2 of Figure 1.

Figure 3 is a top plan view similar to Figure 1 showing a modified form of my invention.

Figures 4, 5 and 6 are sectional views taken on lines 4—4, 5—5, and 6—6 respectively of Figure 3.

A casing 2 which is adapted to house the elements of my remote control is provided which is roughly rectangular in cross section and upon the top of which a cover 4 is adapted to be secured to provide a hollow casing for the apparatus.

In the forward wall of the casing there is provided a pair of bushings 6 and 8 which are rigidly secured in the wall of the casing 2 and in the rear wall in alignment with the said bushings are two more bushings 10 and 12 which are also rigidly secured to the casing 2.

Referring specifically to Figure 1, a rotatable shaft 14 extends through the bushings 6 and 10 and is rotatable therein, the front end of the shaft being flattened, as shown at section 16, and a control knob 18 fitting over the outer end has

a set screw 20 therein which is adapted to be driven down against the flattened face 16 to secure the knob 18 on the shaft.

Adjacent the inner surface of the bushing 6 there is provided a collar 22 held in place on the shaft by a set screw 24 to prevent longitudinal movement of the shaft. The inner end of the shaft 14 is hollow and has secured therein by any desired means the end of a flexible shaft 26, said shaft extending through and connected to the remote radio set, not shown.

Also secured within the bushing 10 is the end 28 of the outer casing of the flexible drive. In like manner a shaft 30 is secured through the stationary bushings 8 and 12 on the left hand side of the apparatus and a flexible shaft 32 housed within a stationary flexible housing 34 is operated by rotation of the shaft 30 through manual operation by a forwardly extending knob 36. Secured to the shaft 30 within the casing 2 is a U-shaped bracket 38 held in place by a set screw 40, one arm of said bracket extending to and operating the movable arms of an off-and-on switch 42 secured to the casing by a screw 44. The circuit connections 46 from said switch are connected to the remote set in any desired manner, the left hand knob therefore operating to turn the whole system on and off by operation of the switch 42 and adapted through the flexible drive 32 to vary the volume of the set. The rotation of the knob 18 on the other hand through its flexible drive tends to rotate the gang condensers of the remote set and therefore to tune the same to various frequencies.

Secured to the shaft 14 by a set screw 48 is a spur gear 50 which is adapted to mate with a large gear 52 supported on a stub shaft 54 which is held in the rear wall of the casing 2 by a nut 56. Also located on the stub shaft is a further gear 58 of smaller diameter, said gears being kept in close contact by a flexed spring disk 59, the two rotating normally together but allowing a certain slippage therebetween if necessary to avoid a stripping of teeth.

The gear 58 mates with a further gear 60 secured to a shaft 62, one end of which is pivoted in the rear face of the casing 2 and the opposite end extends through an inwardly pressed bracket 64 from the forward face of the casing 2 and has press-fitted upon its forward end an indicating needle 66 for rotation therewith. Concentric with the shaft 62 is a helical spring 68, one end of which is secured to the gear 60 and the other to the depending bracket 64 to assist in turning the

gear in one direction and making it easier to manipulate.

In the forward face of the casing 2 there is provided a comparatively large opening 70 over which 5 is secured an irregularly shaped backing plate 72, the ends of which are adapted to lie parallel with the outer surface of the casing. A concealing annular ring 74 is adapted to lie upon the flat edges of the backing plate 72 and upon this annular 10 ring 74 is a transparent disk 76 firmly secured by a bezel 78 which presses a small circular hose gasket 80 against the outer surface of the glass disk 76. The bezel extends in toward the casing, lies over the flat ends of the member 72 and has 15 portions which project through the casing to be bent flat on the inner surface to secure the whole against the casing.

Any suitable lighting means, such as socket 82 and bulb 84, is provided within the casing, the 20 light rays from which project through openings in the casing, backing plate 72, concealing ring 74, and into the glass dial 76. On the forward face of the glass dial there is provided a series of small opaque areas of paint 86 which reflect the light coming from the source causing the same to travel radially through the disk which illuminates the various indicia 88 painted on the rear face of the 25 glass dial.

It will thus be evident that as the right hand 30 knob 18 is rotated, that, as well as controlling the remote gang of condensers, it also operates through the meshing gears 80, 82, 86, and 88 to rotate the indicating needle 86 and indicate the position of the tuning device.

35 In applying this control unit to the instrument panel of an automobile, the two bushings 6 and 8 are adapted to extend through complementary openings in the instrument panel, said instrument panel being indicated by the dotted lines 80. The outer ends of these bushings are threaded and first an angular member 82 is slipped over the bushing and then a lock nut 84 applied which is adapted to be tightened down to secure the unit in position. A dished spring disk 86 is then slid 40 on each of the shafts 14 and 38 and an inverted cup-shaped member 88 is applied which substantially fills the opening in the angular member 82 and conceals the lock nut 84 on the shaft. The two knobs 18 and 38 are then applied to the shafts, 45 pressed in to keep some tension upon the spring disks and their set screws tightened to complete the assembly.

50 The modification of my device shown in Figures 3-6 inclusive is of more elaborate design and includes more control factors than that hereinbefore set forth.

55 Referring now more specifically to Figure 3, a casing 102 is provided which as before is roughly rectangular and is composed of a base and cover 60 and includes in addition side extensions 104 for support purposes. Secured in spaced parallel relation to the front and rear walls of the casing is a supporting plate 106 mounted on a plurality of studs 108 secured in the forward casing wall 65 and cap screws 110 which extend through the plate and into the ends of the studs.

70 In the forward wall of the casing are rigidly supported two spaced bushings 112 and 114. Within each of the hollow bushings are supported 75 a pair of sleeves 116-118 and 120-122, one within the other and within the inner sleeve in each case is rotatably supported the control shaft, 124 and 126 respectively. The innermost sleeve 118 journaling the shaft 124 has secured to its inner end an arm 128 which engages one of the studs

108 to prevent this sleeve from turning. The similar innermost sleeve 120 journaling shaft 126 has an arm 130 secured thereto to which engages a stud 132 to prevent it from rotating in like manner.

5 The outermost sleeve 116 is rotatable on the inner sleeve 118 and within the bushing 112 and has press-fitted upon its outer end a knob 134 for turning the same. To the inner end of the sleeve is secured a movable switch arm 136 which is 10 adapted to operate back and forth between two stationary switch members 138 and 140, said switch being adapted to control the sensitivity of the radio set for local or distant stations. A washer 142 is applied over the outer end of shaft 124 and contacts lightly with the control knob 134 and a second control knob 144 is applied to the 15 end of the shaft and secured thereto by a set screw to hold the washer 142 snugly in place, said last knob controlling the rotation of shaft 124.

20 Secured to the shaft 124 within the casing is a spur gear 146 by set screw 148 and a flexible drive shaft 150 is secured to the end of shaft 124 in any conventional manner to rotate with the same and transmit this rotation to a distant point.

25 Carried on the supporting plate 106 is a stub shaft 152 secured to the plate by nut 154. On this shaft are rotatably supported two gears 156 and 158 which are kept pressed tightly together by a dished spring member 160. Under ordinary 30 circumstances the two gears rotate at the same speed but if for any reason one gear is locked the other may rotate with respect thereto to prevent stripping of the teeth. The gear 158 meshes with the spur gear 146 on shaft 124 and the gear 35 156 meshes with a gear 162 mounted on a parallel shaft 164, one end of which is supported on the plate 106 and the other end proceeds through a bushing 166 in an arm 168 which projects inwardly from one side of the casing. The shaft 40 164 carries upon its outer end an indicating needle 170 for showing the tuning position. It is therefore evident that the right hand knob 144 controls the tuning and dial indication of the set while the adjacent knob 134, concentric with 45 the same control shaft but movable relatively with respect thereto, operates the sensitivity control switch 136, 138-140.

50 Upon the left side of the control panel the inner knob 172 is press-fitted upon the outer rotatable sleeve 122 and rigidly secured to the inner end of the sleeve is a gear 174 which meshes with a second gear 176 held upon the end of a rotatable shaft 178 by screw 180. Adjacent the inner end of the shaft 126 and the rotatable shaft 178 there 55 is a supporting plate 182 which is held in spaced parallel relation to the vertical walls of the casing by supporting studs 132 and is held thereon by screws 184. To this plate are secured by any desired means a rheostat 186 which is operated 60 by the rotating shaft 178, the purpose of said rheostat in the radio circuit being that of tone control from base to treble range. As the knob 172 is rotated it turns the gear 174 which transmits rotation to the gear 176 rotating the shaft 65 178 of the rheostat 186 to control the tone.

70 The control shaft 126 which rotates within the stationary sleeve 120 is mounted directly on a switch and rheostat assembly 188 which is also supported on the plate 182, said switch and rheostat being of the conventional type in which a partial rotation turns on the switch and a continued rotation of the shaft varies the amount of resistance in the circuit. This construction is common in all radio sets and therefore the par- 75

ticular construction of this unit will not be more specifically defined.

The knob 190 is applied to the outer end of the shaft 126 and secured thereto by a set screw 5 to operate the switch and volume control 188. The forward wall of the casing as viewed in Figure 3 has a large circular opening 192 over which is secured a disk 194, the ends of which are crimped through openings in the main casing to 10 secure the same therein. Secured above or in front of the disk 194 is a shielding annular ring 196 having a comparatively large center opening 170 visible from the front. Above this shielding disk is a transparent disk 198 having painted on the rear face thereof suitable indicia 200. Secured over the outer edge of the transparent disk 198 is an annular bezel 202 which is U-shaped in cross section to enclose a rubber washer 204 which presses directly against the glass dial 198. The bezel has an angular edge 206 which is secured to the forward face of the casing by suitable screws 208.

In one end of the casing there is supported a 25 socket 210 which supports any conventional light bulb 212 for a source of light. As the illumination within the casing travels through openings 214 and 216 in the plates 194 and 198 respectively, it travels through the glass dial 198 until it 30 reaches a spot or area of opaque paint or similar material 217 secured to the forward face of the glass dial which reflects the light back through the dial and causes it to travel radially to illuminate the indicia 200 on the rear face. In this 35 modification of my control the right hand knob 144 controls the tuning and the knob 184, slightly to the rear of the knob 144, controls the sensitivity or distance reception. The left hand knob 190 controls the volume and off-and-on switch 40 and its adjacent knob 172 controls the base or treble tone of the receiver.

It should be pointed out that with the switch and rheostat 188 located within the remote control as herein shown, it is only necessary to have 45 one flexible cable, namely 150, which extends to the remotely positioned radio set to turn the gang condensers instead of two as previously used.

I claim:

1. In a device of the class described, a casing,

an indicating dial carried by the casing and having therein an opening adjacent the dial center, a plurality of bearing means carried by the casing in alignment with the opening, a spindle shaft carried in the bearings and projecting through 5 the opening in the dial plate, an indicating needle carried by the projecting end, a gear secured to the spindle, a helical coil spring surrounding the spindle and having one end secured to the gear and the other to one of the bearing means to 10 bias the spindle rotation in one direction and driving means to rotate the gear.

2. In a device of the class described, a casing, an indicating dial carried by the casing and having therein an opening adjacent the dial center, 15 a plurality of bearing means carried by the casing in alignment with the opening, a spindle shaft carried in the bearings and projecting through the opening in the dial plate, an indicating needle carried by the projecting end, a 20 gear secured to the spindle, a helical coil spring surrounding the spindle and having one end secured to the gear and the other to one of the bearing means to bias the spindle rotation in one direction, driving means to rotate the gear, said 25 driving means including a counter shaft carried by the casing, a plurality of gears mounted for independent rotation thereon, spring biasing means to force one gear against the other so that the two will rotate together, one gear 30 engaging the gear on the spindle, and additional gearing engaging the other gear to drive.

3. In a device of the class described, a casing, a dial mounted in the casing, a spindle mounted for rotation in the casing and having one end 35 adjacent the dial, an indicating needle on the spindle to cooperate with the dial, spring biasing means on the spindle tending to maintain the needle at one extremity of its travel, a shaft parallel to the spindle, gearing interconnecting 40 the two, a hollow sleeve mounted on the shaft to act as a bearing, said sleeve projecting through the casing, movable means between the casing and sleeve to support the latter, means projecting from the sleeve and contacting a remote part 45 of the casing to anchor the sleeve and means on the shaft to turn the same and thus move the indicator.

ELBRIDGE F. BACON.
